UNITED STATES PATENT OFFICE.

JOHN JIRASEK, OF DETROIT, MICHIGAN.

FURNACE-ASH-PIT SCREEN SIFTER.

Application filed February 1, 1923. Serial No. 616,362.

To all whom it may concern:

Be it known that I, JOHN JIRASEK, a citizen of the United States of America, residing in the city of Detroit, county of Wayne, 5 State of Michigan, have invented certain new and useful Improvements in a Furnace-Ash-Pit Screen Sifter, and declare the following to be a full, clear, and exact description of the same, such as will enable 10 others skilled in the art to which it pertains to make and use the same, reference being had to the accompanying drawings, which form a part of these specifications.

The object of my invention is to provide 15 a sifting device that can be installed in the ash pit of a furnace for the purpose of screening the small pieces of coal from the ashes as may pass through the fire grates of the furnace, thus preventing the loss of 20 much fuel.

Another object is to provide an ash sifter 25 for screening the coal therefrom, keeping the same within the furnace inclosure, preventing the dust that ordinarily arises 30 from the sifting the ashes by the separate ash sifter.

A further object is to provide an ash sifter that is simple in construction, easily 35 and efficiently operated and can be manufactured at a low cost.

These several objects are secured in their 40 preferred form by the construction and arrangements of parts more fully hereafter described.

Similar parts on all drawings are marked 45 by similar numerals.

Fig. 1, is the front view of the furnace, showing the ash pit screen sifter installed 50 therein.

Fig. 2, is a side view of the furnace showing the general arrangement of the working 55 parts and the relative position of the sifter to the fire grates.

Fig. 3, is a sectional view —AA— of Fig. 60 1, showing the ash pit screen sifter and the supporting frame as arranged in the furnace.

Fig. 4 is a detail of the sifter support, showing the means for attaching same to 65 the furnace parts.

Fig. 5, is an end view of the sifter support with the connecting parts.

Fig. 6, is a detail of the sifter basket.

Figs. 7 and 8 show the side and end view 70 of same.

I will now describe more fully the detailed construction of my ash pit screen sifter, referring to the drawings and the marks thereon.

The general construction of the ash pit 60 sifter comprises a horizontal U-shaped slide support, attached in the upper portion of the ash pit in the furnace, and a wire screen coal basket sliding thereon and so located that it rests directly beneath the fire grates, 65 receiving all particles of ashes and coal that pass through the grates. The ashes passing through the screen sieve and the lumps of coal being retained in the basket and can be easily removed and again placed into the 70 fire to be burned.

The main sifter support —1— is a U-shaped slide made of a flat bar of steel, bent to conform closely with the walls of the furnace ash pit —2—. Near the ends of the 75 support frame —1—, are attached the angle clips —3—, having one of the arms riveted thereto, with the extending arm of the clip bent at right angles to the face of the support, and receiving the support clamps —4—. 80 Clamps —4— being of the required construction to attach to the casting fire box by means of bolts —5—. At the back of the U-shaped sifter support —1—, is attached a support leg —6—, being made of an angle iron, with the top ends bent over to attach to the support frame by means of rivets. The length of the leg —6— is sufficient to reach to the bottom of the ash 85 pit, supporting the frame in a horizontal 90 position. Around the rim of the support frame —1—, are attached small clips —7—, to act as stops for the screen sifter basket. The sifter basket —A— is made of an angle iron frame, supporting the wire basket at- 95 tached thereto, and of such size and shape as will slide within and rest upon the slide support —1—. The outer frame —9— is made of an angle iron bent into a U-shaped frame, with the top leg bent up at an angle, 100 to make the basket support wedge snugly between the slide bars of support —1—. The angle frame —10— forming the front of the basket support, is left square, same being for support only. Around the bottom 105 of the frame —9—, is a heavy wire rim —11— which supports the wire screen sieve —12—, forming the basket sifter. The wire rim —11— is attached to the frame —9— by means of small wire loops —13—. The 110

front of the sifter basket is provided with a handle —14—, for shaking and removing the basket from the ash pit.

In using my ash pit screen sifter, after 5 the slide support is installed in the ash pit of the furnace, the basket can be placed on the slide, and pushed within the pit directly beneath the grates, through the door —15— in the front of the furnace. The basket being 10 supported by the angle flanges of the side frame —9—. Should the basket become filled, the ashes may easily be screened out by shaking same back and forth on the slide support, leaving the coal separated to be re- 15 moved and placed in the furnace again.

Having fully described my furnace ash pit screen sifter, what I claim as my invention and desire to secure by Letters Patent is;

1. An ash pit screen sifter of the character described, comprising a wire screen basket, angle slides for the sides of said basket, means for attaching said slides to the basket, a support slide frame for holding the basket in place beneath the fire grates of the 25 furnace supports for attaching said frame permanently to the walls of the ash pit and means for operating said sifter for separating the coal from the burned ashes.

2. An ash pit screen sifter of the character 30 described comprising a wire screen basket, a supporting slide frame attached to the

top of said screen basket, means for attaching same to the basket, said slides having the sides bent outward to engage projecting supports, a supporting slide rack conforming to the shape of the basket supporting frame and engaging the slides thereon, means for attaching the support slide rack to the ash pit walls and means for sliding the sifter basket in and out of the pit on 35 said sliding support-rack.

3. An ash sifter of the character described comprising a screen basket conforming approximately to the walls of a furnace ash pit, a metal frame fitting into the top of 40 said screen basket, said frame having overhanging walls along the sides thereof forming sliding supports for the basket, fasteners for attaching the basket to the metal frame, a draw bar handle at one end of said basket 45 for operating the sifter basket, a supporting slide rack conforming to the shape of the basket frame and engaging the slides thereon allowing the sifter basket to be moved in and out of the ash pit, brackets attached to 50 the supporting slide rack for permanently installing same in the ash pit by attaching same to the walls thereof.

In witness whereof I sign these specifications.

JOHN JIRASEK.
